UNITED STATES PATENT OFFICE.

LEWIS W. CLEVELAND, OF PORTLAND, MAINE, ASSIGNOR OF THREE-FOURTHS
TO CLARENCE L. MARSTON, LEWIS A. BARKER, AND DENNIS A. MEAHER,
ALL OF SAME PLACE.

ELECTRICAL DOOR-BELL PULL.

SPECIFICATION forming part of Letters Patent No. 447,748, dated March 3, 1891.

Application filed December 1, 1890. Serial No. 373,207. (No model.)

To all whom it may concern:

Be it known that I, LEWIS W. CLEVELAND, a citizen of the United States, residing at Portland, in the county of Cumberland and State 5 of Maine, have invented certain new and useful Improvements in Electrical Door-Bell Pulls; and I do hereby declare the following to be a full, clear, and exact description of the invention, such as will enable others skilled in 10 the art to which it appertains to make and use the same.

Figure 1 is a perspective view of this device. Fig. 2 is a central longitudinal section of the device, showing the pull at rest. Fig. 15 3 is a like view, but showing the pull as in position when the bell is being rung.

This invention belongs to that class of devices known as "electrical door-bell pulls," and the novelty consists in the construction 20 and combination of the parts in the manner and for the purposes which will hereinafter be fully set forth and claimed, reference being had to the accompanying drawings.

The chief trouble with all electric arrangements for door-bell pulls is that the electric 25 points or binding-posts are more or less exposed to the action of the weather, and when the weather is wet or damp there is a constant leakage and wearing of the batteries and they 30 soon give out. The aim of the present invention is to overcome this.

In the drawings, A represents any ordinary handle for a bell-pull, and B the escutcheon fixed to the door-frame. This escutcheon is 35 recessed on its face at b about the central opening b' through it to afford a seat for the end of the shank a of the pull. On the inner face side of the escutcheon is fixed the hollow projection b², to which the cylinder or 40 sleeve C is fixed at one end by screws c. This cylinder has inside of it the most of the operative or movable parts of the device, and is of proper length and size for that purpose.

The spindle a' of the pull is located within 45 the cylinder C, and is adapted to be moved back and forth therein through the projection b² and the opening b' in the escutcheon. Between its end and the inner face of the escutcheon is placed around the spindle the 50 spiral spring D, by means of which the han-

dle is automatically returned to position and kept normally against the escutcheon, as shown in Fig. 2. When the pull is drawn out, as in Fig. 3, to ring the bell, the metal spindle E, which is beyond but in alignment with the 55 pull-spindle a', is forced inward by the spiral spring F about it, fixed between its headed end e and the hard-rubber piece G, which is fastened by any suitable means in the outer end of the cylinder or sleeve C, leaving a portion of it beyond the cylinder. This movement of the spindle E brings its metallic head 60 e in contact with the binding-posts H H', fixed in said hard rubber and completes the electric circuit between the wires I I'. When 65 the connection is made the spindle E is completely insulated.

This device is very simple in its structure and prevents any leakage of the batteries, the hard rubber that carries the binding-posts 70 being placed beyond the access of dampness or the effect of the weather. Its parts are very easily reached for repairs. While it is not broadly new to make connection of the electric circuit by means of a pull-spindle 75 having a spring about it, yet in my device the hard rubber is permanently and securely fixed, and the binding-posts are in like manner secured and firmly fixed in position therein. The circuit is made by direct contact 80 with the said binding-posts of an independent and spring-actuated piece of metal, and best of all, when the electric circuit is complete there is no danger of its being interrupted 85 by reason of contact with any other parts, since the means that effect the closure of the circuit are themselves insulated in fact.

Having thus described my invention, I claim—

1. In an electrical door-bell pull, the combination of the handle and spring about its spindle, whereby it is normally held in place, with a second spring-actuated spindle and the insulating material through which said spindle is movable, and the binding-posts in 90 said material, whereby when the handle and its spindle are drawn out said second spindle is insulated by its spring action and makes connection between said binding-posts, substantially as described. 95

2. In combination with a door-escutcheon and a metal cylinder C, fixed thereto at one end, the handle A and its spindle and the spring about it inside said cylinder, and the 5 hard rubber G, fixed in the opposite end of the cylinder and projecting beyond said cylinder, and the binding-posts and spring-actuated and headed spindle E, substantially as and for the purposes set forth.
- 10 3. In an electric door-bell pull, the combination of the spring-actuated handle and the insulating material and binding-posts therein with the second spring-actuated spindle in alignment with the first spindle, movable 15 through said insulating material, and all in the manner and for the purposes described.
- 15 4. In an electric door-bell pull, substantially as described, the combination of the

door-escutcheon and sleeves or cylinder attached thereto, the hard-rubber or insulating material secured in and to the outer end of said sleeve or cylinder, and the binding-posts secured to said material, and the headed and spring-actuated metal spindle movable within said sleeve or cylinder and also through 20 said insulating material, and the handle and its connections normally holding said headed spindle out of contact with the binding-posts, substantially as and for the purposes set forth.

In testimony whereof I affix my signature in 25 presence of two witnesses.

LEWIS W. CLEVELAND.
